HIGHWAY SAFETY SIGN

Richard E. Diggs, 210 N. River St.,
Carthage, Mo. 64836

Filed Feb. 13, 1975, Ser. No. 549,504

Term of patent 14 years

Int. Cl. D10—06

U.S. Cl. D10—111

FIG. 1

FIG. 2

FIG. 3

FIG. 4

FIG. 5

FIG. 6

FIG. 7

FIG. 9

FIG. 8

FIG. 1 is a rear elevation of a highway safety sign showing my new design.

FIG. 2 is a front elevation of the highway safety sign of FIG. 1.

FIG. 3 is an end elevation as seen from the left of FIG. 2.

FIG. 4 is a rear elevation of a second embodiment of the new design.

FIG. 5 is a front elevation of the highway safety sign of FIG. 4.

FIG. 6 is an end elevation as seen from the right of FIG. 5.

FIG. 7 is a rear elevation of a third embodiment of my new design.

FIG. 8 is a front elevation of the highway safety sign of FIG. 7.

FIG. 9 is an end elevation as seen from the left of FIG. 8.

The reflective surfaces of the signs are shaded to indicate contrast.

I claim:

The ornamental design for a highway safety sign, as shown and described.
